(57) **CLAIM**

The ornamental design for a mattress and linen restraining device, as shown and described.

DESCRIPTION

FIG. 1 is a perspective view of the mattress and linen retaining device showing our new design, in use with a mattress.

FIG. 2 is a cross-sectional view of the mattress and linen retaining device taken along the line 2—2 in FIG. 1.

FIG. 3 is one side view of the mattress and linen retaining device shown with the mattress removed. The opposite side view is the mirror image.

FIG. 4 is one end view of the mattress and linen retaining device.

The opposite end view is the mirror image.

FIG. 5 is a top view of the mattress and linen retaining device; and,

FIG. 6 is a bottom view of the mattress and linen retaining device.

In the drawings, the broken lines represent environmental structure forming no part of the claimed design.
